UNITED STATES PATENT OFFICE.

EARL W. TURNER, OF KOKOMO, INDIANA.

TIMER MECHANISM.

1,417,361.

Specification of Letters Patent. Patented May 23, 1922.

Application filed October 30, 1919. Serial No. 334,501.

To all whom it may concern:

Be it known that I, EARL W. TURNER, a citizen of the United States, residing at Kokomo, in the county of Howard and State 5 of Indiana, have invented certain new and useful Improvements in Timer Mechanism, of which the following is a specification.

This invention relates to timer mechanisms for the ignition systems of explosive engines 10 and has for its object to provide an extremely compact timer structure which may be readily applied to the interior of the casing or supporting mechanism of conventional timers now in use for replacing worn 15 or broken parts.

Another object is the provision of a timer mechanism including an improved type of rotary contact element which, due to its extreme simplicity, is capable of economical 20 manufacture and is not liable to become broken or damaged.

With these and other objects in view as will appear as the description proceeds the invention comprises the novel features of 25 construction combination of elements and arrangement of parts which will be more fully described in the following specification and set forth with particularity in the claims appended hereto.

30 Figure 1 represents a rear elevation of the improved timer, the drive shaft therefor being shown in section.

Figure 2 represents a diametrical sectional view in the plane of the section line 2—2 of 35 Figure 1.

Figure 3 represents a sectional view at right angles to Figure 2 taken in the plane of the section line 3—3 of Figure 1.

Figure 4 represents a perspective view of 40 the contact member removed.

Referring to the drawing in detail, wherein similar reference numerals designate corresponding parts throughout the several views, the numeral 5 indicates a cup-shaped 45 insulator the size of which may be varied according to the size and type of timer mechanism in connection with which the device is to be used. The circular body portion of the insulator is formed with a central opening 6 and in the space between the edge of 50 the opening and the annular flange 7 a series of equidistant relatively stationary contact members 8 are anchored in the insulator. The contacts 8 are arranged with their rear 55 surfaces flush with the rear surface of the body of the cup-shaped insulator and the

latter is preferably formed of a fibrous material having the requisite electrical resisting qualities in order that the contacts may be fitted therein during manufacture of the 60 article for economical reasons and for rigidity and permanency of the structure. The terminals of the conductors 9 forming a part of the ignition system of the engine are connected with the contacts 8 and are extended 65 from the back of the insulator and are properly connected with the electrical devices of the ignition system.

The cam shaft 10 or other rotatable part of the explosive engine which is utilized to 70 operate the timer mechanism is extended into the rear open portion of the cup-shaped insulator 5 and supports a sleeve 10* having a radially projecting arm 11 constituting a support for the rotary contact element designated generally by the numeral 12. The sleeve is rigidly and movably secured in position upon the end of the shaft 10 by a lock nut 13 or equivalent fastening device which is freely movable through the opening 80 6 in the center of the flat body portion of the insulator facilitating convenient removal of the latter from the sleeve and shaft terminal.

One end of the rotary contact member 12 85 is curved, the axis of the curve being the same as the axis of the circular series of contacts 8, and apertures 14 are formed in the curved terminal for receiving screws rigidly and electrically connecting the end of the 90 contact with the arm 11. The opposite extremity of the contact is rolled or of cylindrical form as indicated at 16 and the adjacent portion of the strip of material from which the contact is constructed is formed 95 with an off set 17 disposing the rolled terminal 16 thereof in the plane of and in contact with the rear surface of the insulator 5. The strip of material from which the rotary contact 12 is formed has sufficient resiliency 100 and the form of the contact is such as to normally maintain the rolled terminal in engagement with the rear face of the insulator under sufficient pressure to ensure proper electrical connection between the rotary contact member and the stationary contact members as the latter are successively engaged during rotary motion of the member 12.

Owing to the shape and compactness of 110 the timer structure, the latter, with proper variations in dimensions may be readily ap-

plied to conventional types of timer casings now in use and the replacement of the usual internal timer mechanism by my improved timer is a matter of slight inconvenience and 5 advantageous from the standpoint of expense owing to the utter simplicity of the device and the possibility of extreme economy in its manufacture.

The rolled extremity of the rotary contact 10 member 12 is provided with a solid tip 12^a of stellite or bronze as indicated by the heavy line in Figure 4, having the necessary wear-resisting and non-corrosive qualities to prolong the life of the timer and eliminate

necessity of periodical cleaning of the contact surfaces thereof.

What I claim is:

In a timer structure for explosive engines, a movable contact element adapted for connection with a timer arm constructed of resilient material including a body curved concentrically to the axis of the timer arm and having one end rolled and having the medial portion offset.

In testimony whereof, I affix my signature hereto.

EARL W. TURNER.
